FABRIC GLOVE AND METHOD OF
PRODUCING THE SAME

Aaron Charney, Chicago, Ill.

Application April 7, 1941, Serial No. 387,133

5 Claims. (Cl. 2—169)

My invention relates to improved methods of making woven or like fabric gloves and to new fabric gloves made in accordance with such methods.

In order to make a satisfactory dress or semi-dress glove, it is essential that a fabric be employed which does not possess "stretch" in a direction running longitudinally of the pattern, that is, along the length of the fingers, but which does possess "stretch" in a transverse direction. By "stretch" is meant sufficient extensibility so that the fabric is stretchable to a substantial extent, preferably with at least some resiliency so that the fabric, having been stretched or extended, will, in part at least, return to its normal unstretched position.

Because of the characteristics considered essential in a glove fabric, it has heretofore been impossible to produce a satisfactory glove from a woven fabric material, such as cotton or the like, which has a tight warp and woof. This type of material is only very slightly extensible either longitudinally or transversely. The impossibility of using such materials in the past has resulted in restricting very definitely the materials adapted for use in the production of fabric gloves, notwithstanding the fact that among these woven materials with a relatively tight or substantially non-stretchable warp and woof are many materials which, considering their finish, color, relatively low price and other factors, would be ideal materials for making certain types of fabric gloves.

The principal object of my invention is the provision of an improved method of making fabric gloves.

Another object is to produce a satisfactory, salable glove from relatively tightly woven, substantially non-stretchable materials heretofore considered useless for the production of dress or semi-dress or fitted gloves.

A further object is the provision of a method of producing a glove which is particularly adapted for use with tightly woven, substantially non-stretchable fabrics.

In carrying out my invention, I treat the cloth so that it will possess "stretch" in one direction but, in a direction at right angles thereto, it will not possess "stretch." To this end, I first cut the cloth in strips running along the bias, whereby, both longitudinally and transversely of the resulting strips, the cloth becomes stretchable. I then treat the strips to remove the "stretch" in one direction, cut the glove patterns therefrom so that the patterns run in a direction in which the

cloth has no remaining "stretch," and sew the glove patterns together in the ordinary way. The result is a fabric glove which does not have "stretch" in a direction running longitudinally of the fingers but does possess "stretch" in a transverse direction. With such a glove, the fingers do not become elongated but the glove shapes itself to the hand and, when the hand is closed, there is enough resiliency to permit the fabric to stretch sufficiently, transversely of the length of the glove, to adjust itself to the position of the hand.

I have illustrated the steps of the method in the accompanying drawing, wherein

Fig. 1 is a plan view indicating the manner in which strips are cut from the cloth;

Fig. 2 is a plan view of one of the strips before it has been treated to modify its shape and stretching characteristics;

Fig. 3 is a plan view of the same strip as that shown in Fig. 2, but illustrating its conformation after its stretching characteristics have been modified;

Fig. 4 shows the manner in which the glove patterns are laid out on the treated strip and cut therefrom; and

Fig. 5 is a view of the completed glove.

In carrying out the method of my invention, I utilize a strip of cloth 10 having a tight warp and woof and therefore substantially non-stretchable in a transverse or a longitudinal direction. I then cut strips 11 from this cloth on the bias, these strips, as shown, being cut parallel to the line a but transversely of the line b. These strips are removed and will then have generally the shape shown in Fig. 2, which, for purposes of illustration, has been enlarged. On Fig. 2, I show the line a', which illustrates the bias line, now running longitudinally of the strip 11, and the line b', illustrating the bias in the opposite direction, now running transversely of the strip 11. These lines correspond to the dotted lines a and b identifying the parts in the full strip 10.

The next step of the method is to remove all of the "stretch" along either, but not both, the line a' or the line b' and to produce a strip 11' from which the glove patterns may be cut and a satisfactory glove produced. I find that there are several ways in which this may be accomplished, it being kept in mind that, ordinarily, mere mechanical stretching will not produce the desired result. I have found that the preferred and least expensive method is to uniformly moisten the strip 11, stretch it longitudinally, that is, in a direction along the line a' substantially the maxi-

mum amount, and hold the strip in stretched condition until it is dry. The strip may be ironed while it is in stretched condition to accelerate its setting in permanently stretched condition. It may be treated with several types of substances, such as sizing or the like, to facilitate the setting operation. Whatever the specific means employed may be, the purpose is to produce a strip 11', such as shown in Fig. 3, which, because it has been stretched, will be longer but narrower than the strip 11 and will be stretchable in a transverse direction but not in a longitudinal direction.

The strip 11' having been so produced, the next step is to lay out glove patterns and cut the glove parts therefrom. I show in the drawing a combination palm and back pattern 12, a thumb pattern 13, and a number of fourchettes 14. It will be noted that all of these patterns run longitudinally of the strip 11', that is to say, in the direction in which the strip 11 has substantially no stretch. These patterns are then sewed together in the usual manner to produce a glove 15.

The glove 15 produced in accordance with this method from the described material is substantially nonstretchable in the direction shown by the single arrow *c* near the fingers. Transversely of the glove, in the direction of the double arrow *d*, however, the material of the glove is stretchable. Because of the treatment of the fabric, however, the glove in this direction also possesses a certain amount of resiliency so that it will shape itself to the hand and adjust itself to movement of the hand. I call attention again, however, to the fact that, along the direction of both the arrows *c* and *d*, the material of the glove is on the bias.

By means of the present invention, I have been able to produce very desirable gloves from many types of materials which heretofore have not been considered suitable glove materials. Thus, for example, I have been able to produce relatively inexpensive dress gloves having a great demand and ready sale.

While the specific details which I have disclosed hereinabove may be followed to produce the most satisfactory results, those skilled in the art will understand that the general principles of the invention may be modified somewhat without departing from the spirit thereof. As an example, it is not essential that the strips 10 be utilized in the same form and shape that I disclose them, and it is possible to take a relatively quite large section of cloth and impart a permanent stretch to it along one bias line, and cut the gloves directly from such relatively large section of cloth. In producing gloves, it is a frequent practice to cut several patterns at one time from a stack of several thicknesses of cloth. I may employ many of these common expedients without departing essentially from the teachings of the invention.

While I have described my invention in detailed form, the full scope of the invention is not to be limited other than as is defined by the claims.

What I claim as new and desire to protect by Letters Patent of the United States is:

1. The method of producing gloves from a fabric having substantially no "stretch" along the warp or woof but stretchable along the bias in either direction, which includes the steps of removing the "stretch" in one direction along the bias, cutting glove patterns from such fabric

so that the length of the resulting glove patterns runs along the bias in said direction in which the stretch has been removed, and sewing said patterns to produce the gloves, the construction being such that the sewing threads will not readily break when stress is applied to the glove material in the direction of the length of the glove.

2. In a method of making gloves from a woven or like fabric of the type which does not possess "stretch" in either a longitudinal or transverse direction and wherein, after cutting the glove patterns, the latter are sewed to form gloves, the steps which include cutting said fabric on a bias whereby to produce strips having "stretch" in both the longitudinal and transverse directions, moistening said fabric, stretching said moistened fabric strips in a single direction and maintaining the same in stretched condition while drying, whereby, after drying, the strips possess "stretch" in only one direction, and then cutting glove patterns from said fabric strips so that the remaining "stretch" is in the direction of the width of the resulting glove patterns.

3. In a method of making gloves from a woven cotton or like fabric which, as woven, does not possess "stretch" in either a longitudinal or transverse direction and wherein, after cutting the glove patterns, the latter are sewed to form gloves, the steps which include cutting said fabric on a bias so as to impart thereto "stretch" characteristics in both longitudinal and transverse directions, removing the "stretch" from the said cut fabric in only one of the said directions by a procedure which includes the moistening of the fabric, and cutting glove patterns from said fabric so that the "stretch" along the other of said directions lies along the width of the resulting glove patterns.

4. A method of making gloves from a woven or like fabric of a type which does not possess "stretch" in either a longitudinal or transverse direction, which includes the steps of cutting said fabric on a bias whereby the said fabric acquires "stretch" in both the longitudinal and transverse directions, moistening said cut fabric, stretching said moistened fabric in a single direction so as to remove the "stretch" in only one of said directions, then cutting glove patterns from said fabric so that the remaining "stretch" is in the direction of the width of the resulting glove patterns, and sewing said patterns to produce the gloves, the construction being such that the sewing threads will not readily break when stress is applied to the glove material in the direction of the length of the glove.

5. A method of making gloves from a woven or like fabric of a type which does not possess "stretch" in either a longitudinal or transverse direction, which includes the steps of cutting said fabric on a bias whereby the said fabric acquires "stretch" in both the longitudinal and transverse directions, removing the "stretch" from said cut fabric in only one of said directions, then cutting glove patterns from said fabric so that the remaining "stretch" is in the direction of the width of the resulting glove patterns, and sewing said patterns to produce the gloves, the construction being such that the sewing threads will not readily break when stress is applied to the glove material in the direction of the length of the glove.

AARON CHARNEY.
